UNITED STATES PATENT OFFICE

122,926

DESIGN FOR A LOOP ANTENNA

William P. Lear, Dayton, Ohio, assignor to Lear Avia, Inc., Dayton, Ohio, a corporation of Illinois

Application March 14, 1940, Serial No. 90,916

Term of patent 14 years

To all whom it may concern:

Be it known that I, William P. Lear, a citizen of the United States, residing at Dayton, in the county of Montgomery, and the State of Ohio, have invented certain new, original, and ornamental Design for a Loop Antenna, of which the following is a specification, reference being had to the accompanying drawing forming part thereof, in which:

Fig. 1 is a perspective view of a loop anter showing my new design;

Fig. 2 is a front elevational view; and
Fig. 3 is a side elevational view thereof.

I claim:

The ornamental design for a loop anten substantially as shown.

WILLIAM P. LEAR
